UNITED STATES PATENT OFFICE.

CHARLES KOFF, OF NEWARK, NEW JERSEY.

HANDLE FOR SATCHELS AND THE LIKE.

1,157,400.

Specification of Letters Patent.

Patented Oct. 19, 1915.

Application filed April 20, 1915. Serial No. 22,537.

To all whom it may concern:

Be it known that I, CHARLES KOFF, a citizen of the United States, residing in the city of Newark, in the county of Essex and State of New Jersey, have invented certain new and useful Improvements in Handles for Satchels and the like, of which the following is a full, clear, and exact description, such as will enable others skilled in the art to which it pertains to make, construct, and use the same, reference being had to the accompanying drawings, and to numerals of reference marked thereon, forming a part of this specification.

15 My invention relates to improvements in handles for satchels and the like, which are composed of two metallic shells, preferably covered with leather or other similar elastic material, and adapted to be attached to a satchel, bag, or suit case, by means of suitable rings or loops secured to the frame of the bag or suit case.

The object of my invention is to provide a handle, comprising an upper and lower shell united in such a manner, and of such form, as to give a good hold for the hand. The upper and lower shells are so constructed and arranged that the weight of the bag is upon both of the shells, which gives rigidity, strength and wearing qualities to the handle, and at the same time, providing a handle having the appearance of being made entirely of leather.

Another object of my invention is to provide a simple, inexpensive and more effective handle of this character, having certain details of structure, hereinafter more fully described. The blanks from which the handles are formed, are stamped or cut from suitable sheet metal, and are of such a shape as to lend themselves readily to manufacture by the use of ordinary tools and dies.

In the accompanying drawings, Figure 1 represents a perspective view showing my improved handle applied to a portion of a bag frame. Figs. 2, 3 and 4 represent respectively, a plan view, a side elevation and an under plan view. Figs. 5 and 6 represent respectively, side elevations, partly in section, of the upper and lower sections of the handle. Fig. 7 represents an enlarged transverse section of the handle on line $\alpha-\alpha$ of Fig. 1. Fig. 8 represents an enlarged transverse section of the handle taken on lines $\alpha-\alpha$ of Fig. 3; and Fig. 9 represents

a longitudinal fragmentary section of one end of the handle.

Similar numerals of reference refer to like parts throughout the specification and drawings.

In the said drawings, 1 represents the upper section of the body of the handle; 2 the lower section of the same; and 3 represents a covering of leather secured around the body sections in any convenient or desired manner. The upper section 1 of the body of the handle, is preferably curved, as illustrated in Fig. 7 of the drawings, and terminates at each end in hooks or eyes 4, extending downwardly and inwardly, which are formed on said section during the process of manufacture, and designed to receive the rings or loops 5 of the satchel or bag, as illustrated in Fig. 8 of the drawings. The lower section 2 of the body of the handle is preferably curved, as illustrated in Fig. 7 of the drawings, and provided at each end with countersunk apertures 6, which when the upper section is fitted into the lower section, the apertures 6 are in alinement with the hooks 4 of the upper section, so that a ring or loop 5 may be passed through the apertures of the lower section and the hooks of the upper section. The lower section is of a width sufficient to receive not only the downwardly curved opposite edges of the upper section therebetween, but also the thicknesses of leather covering extending into the joint, and thus retained in place.

The ends of the lower section of the body of the handle, are preferably provided with inwardly extending slots or openings 7, to receive the inwardly extending hooks or eyes 4 of the upper section 1 of the body of the handle, so that when the upper section is snapped into the lower section, in order to unite said parts, the same will readily be assembled, in order to bring the countersunk apertures 6 of the lower section of the body of the handle into alinement with the hooks or eyes 4 of the upper section. The preferred form of the handle is shown in the accompanying drawings, but other forms and designs may be employed.

While I may simply inclose the sections with leather, I preferably paste a leather covering upon the lower section, the edges of the leather being turned in between the upper and lower sections, and in like manner,

I paste leather to the upper section, the edges of said leather being covered and concealed by the turned leather of the lower section.

5. Experience has demonstrated that the organization above described is a highly efficient one, and I do not wish to be limited to the exact details of construction and combination herein shown and described, as obvious modifications thereof will present themselves to those skilled in the art, and such departures I consider within the scope and terms of my claims.

I claim:

15. 1. A handle of the character described, comprising an upper section having hooked ends, and a lower section adapted to receive said upper section, said lower section having apertured ends, the apertures in the ends of the lower section being in alinement with the hooks of the upper section.

20. 2. A handle of the character described, comprising an upper section having hooked ends, and a lower section adapted to receive said upper section, said lower section having apertured ends, the apertures in the ends of the lower section being in alinement with

the hooks of the upper section and a cover for the upper and lower sections.

3. A handle of the character described, comprising an upper section having hooked ends, and a lower section adapted to receive said upper section, said lower section having apertured ends, the apertures in the ends of the lower section being in alinement with the hooks of the upper section and a ring secured in each end of the handle, said rings passing through the apertures of the lower section and the hooks of the upper section.

4. A handle of the character described, comprising an upper sheet metal section, having inturned ends, and a lower sheet metal section adapted to receive said upper section, said lower section having countersunk apertured and slotted ends, said apertures in the ends of the lower section being in alinement with the inturned ends of the upper section.

This specification signed and witnessed this 17th day of April, 1915.

CHARLES KOPF.
